RECORDER KEY FOR WATCHMEN'S CLOCKS

Martin Jauch, Park Ridge, Ill., assignor to Detex
Watchclock Corporation, New York, N. Y., a
corporation of Delaware

Application March 15, 1950, Serial No. 149,731

17 Claims. (Cl. 346—57)

1

This invention relates to watchmen's clocks and more particularly to improved mechanism associated with watchmen's clocks for rendering impressions on record-receiving means within the clock.

One or more portable watchmen's clocks are customarily utilized to service a multiplicity of stations arrayed at random points throughout a tour of inspection. At each station there is secured a recording key for forming an impression on record-receiving means housed within the casing of the clock. The record-receiving means may comprise a time-calibrated tape displaced within the clock as a function of time in conformance with the clock-action, and an individualized impression may be made on the tape by dies in each recording key indicative of the time at which that particular impression was formed. Thus there is provided a permanent and complete record of the watchman's tour of inspection.

In currently used watchman's clock systems recording keys are provided having suitable embossing or printing dies mounted therein, the dies being supported within the key by means of one or more pivotally mounted carriers actuated by suitable means within the clock. In order to prevent the impression of the key at one station from overlapping and destroying the impression made at the preceding station, the die positions are varied within the respective keys. It has been found, however, that such recording mechanisms do not provide uniformly good impressions, the quality being varied, for example, due to variations in radial distances of the dies from the pivotal point of the carrier.

It is, therefore, an object of this invention to provide a recording key assembly wherein recording dies or other impression-rendering means may be mounted at any one of a plurality of positions without jeopardizing the effectiveness of the impression-forming operation.

It is another object of the invention to provide a recorder key assembly wherein the die pressures are equalized during each impression-forming operation to improve the legibility and appearance of the impressions.

A further object of the invention is to provide a novel key actuating linkage to be housed within the clock casing to initiate and effect proper actuation of the recorder key, and whereby an impression cannot be made unless the key is properly orientated within the clock.

Yet another object of the invention is to provide novel means for indicating to the operator

2

when an impression has been formed on the record tape.

According to the invention there is provided a recorder key having a die-carrier member which is spring-supported in a manner affording full floating support in the plane of movement thereof. A locking linkage is provided within the key to maintain the die-carrier in an inoperative position until such time as the key is properly inserted in the clock, and suitable actuating means are provided within the clock to initiate movement of the die-carrier to form an impression on the record tape. In addition a click member is provided to indicate when the die-carrier has been properly actuated to form an impression.

These and other objects of a typical recorder key and actuating mechanism formed according to the invention may be better understood by reference to the following specification in conjunction with the accompanying drawings in which:

Fig. 1 is a perspective view of a portable watchman's clock and a recorder key showing the key being received in the clock;

Fig. 2 is a view in side elevation of a recorder key;

Fig. 3 is a view in end elevation of the key shown in Fig. 2;

Fig. 4 is an enlarged view in longitudinal cross-section showing the internal mechanism of the recorder key;

Fig. 5 is a view in end elevation of the key-house assembly adapted to actuate the recorder key and shown isolated from the portable clock in which it is mounted;

Fig. 6 is a view in side elevation of the key-house assembly shown in Fig. 5; and

Fig. 7 is an enlarged perspective view of the key-house assembly showing the structural detail thereof.

A recorder key formed according to the invention is designated by numeral 10 and is adapted to be secured by means of an apertured heel portion 10a to a station box or wall bracket 11 which may be disposed at any random point along the tour of inspection of the watchman. The key is preferably pivotally mounted by means of its apertured heel on an immovable pin 12 so that it may be swung outwardly to be received in a key-house 13 of a portable watchman's clock 14.

Broadly, the watchman's clock comprises clock-movement (not shown) which actuates a feeding mechanism (not shown) for indexing a record

tape 15 (Fig. 7) between suitable reels mounted within the clock casing.

The record tape 15 is furnished with suitable time-calibrations 16 printed along one edge and is arranged in the clock to pass through the key-house assembly 13 as shown in Fig. 7, with the time-calibration corresponding to the time of day disposed precisely within the key-house.

The key 10 is formed with a horizontal slot 17 adapted to receive the record tape 15 at such times as the key is received in the key-house 13, the slot 17 being defined by a shank portion 18 and an underlying shelf-portion 19 formed integrally therewith. A female die member 20 is formed in the inner surface of the shelf 19 for coaction with a corresponding male die member 21 formed on the depending end of a vertical arm 22 slidably mounted within the shank portion 18 in suitable guide-ways 23, which guide-ways may be enlarged to permit limited turning and lateral movement of the arm 22. The arm 22 is affixed by its upper end to a horizontal carrier bar 24 housed within an enlarged chamber formed in the shank. A pair of coil springs 25 seated in depressions 25' in the shank bear against the under edge of the carrier bar 24 to bias the carrier bar upwardly against contoured abutments 26 formed integrally with the shank.

The carrier bar 24 and hence the male die 21 are normally locked in the upper, inactive position by means of a horizontally-slidable sear element 27 biased in the direction of its locking position by a coil spring 28 seated in a recess 28'. The locking sear 27 is provided with a depending foot 29 having an oblique cam surface 29' engaged by a cam surface 30 formed on a short arm 31 pivotally mounted to the shank at 32. The pivotal arm 31 is formed with a second cam surface 33 normally disposed obliquely at the inner end of the key slot 17.

The above locking linkage is released when the key is inserted in its house and then driven home so that the surface 33 of the unlocking lever 31 is engaged by an unlocking bar 34 affixed in the throat of the key-house 13 (Figs. 5 and 7). As the key is driven home the unlocking bar 34 causes the arm 31 to pivot upwardly, causing the locking sear 27 to be driven horizontally to the right by coaction of their mutually engaged surfaces 30 and 29', thereby to release the carrier arm 24, which is then free to be depressed downwardly to form an impression on the tape by means of suitable actuating linkage disposed within the key-house as described below.

The key-house 13 comprises a key-receiving channel 35 (Fig. 5), having a cross-sectional configuration in the form of an inverted T, which guides the entering key so that the moving record tape 15 is laterally received within the slot 17. The key is likewise formed with a cross-sectional configuration of an inverted T, thereby insuring proper orientation of the key within the house at all times. With the key disposed in the house and the unlocking linkage actuated, the embossing dies 20 and 21 of the key are brought into engagement by means of a finger-lever 36.

The lever 36 is pivotally secured by a pin 37 at its inner end to the rear wall of the key-house and is formed with a cam surface 36' in its lower edge adapted to engage a plate 37' pivotally mounted on a longitudinal axis by means of a pin 38 and apertured ears 39. The plate 37' is biased upwardly by a coil spring 41 surrounding a vertical guide pin 42 received in an enlarged hole 43 adjacent the free edge of the plate.

The under surface of the pivot plate 37 is formed with a pair of depending lugs 44 (Fig. 6) which are adapted to bear downwardly on the upper edge of the spring-supported carrier 24 of the recording key, when the latter is properly inserted in the key-house. Thus when the finger lever 36 is depressed the pivotal plate 37 will drive the carrier bar 24 downwardly to bring the die members 20 and 21 into engagement across the surfaces of the record tape 15 to form an impression thereon.

In order to indicate to the operator when a record has been made, a signaling mechanism is provided in the key-house including a pivotal click-finger 45 having a nose portion 46 extending through an aperture 47 in the inner wall of the key-house. The nose portion 46 is adapted to be engaged by a corner 48 of the pivot plate 37 to be pivoted outwardly thereby against the action of a spring 49 until such time as the corner of the plate passes the nose 46, at which time the finger 45 snaps to its initial position against the rear wall of the key-house, producing a clicking sound audible to the operator and indicating that the linkage has been suitably actuated to form an impression on the tape.

Referring to Fig. 4, it will be seen that the carrier bar 24, by virtue of the floating support in its plane of movement, tends to equalize die-engaging pressure throughout the working areas thereof. Moreover, limited lateral play may be provided in the guide-way 23 for the movable die carriers 24 so that the female die may pilot the male die into proper vertical alignment, thereby expanding the tolerance ranges which must be met in manufacture. In this respect the cost of manufacture of a wholly efficient key may be materially reduced.

The novel assembly also enables the mounting of dies at any one of a plurality of positions along the length of the carrier bar 24, such as that shown by broken lines in Fig. 4, without jeopardizing the impression-forming efficiency. Thus it is possible to mount the dies in various recorder keys so that the impressions formed will not overlap or otherwise obliterate each other even though the time required for the watchman to move between closely adjacent stations may be so small that the record tape will not have moved within the clock a distance great enough to provide the necessary spacing of the impressions. The impression character *a* on the tape 15 (Fig. 7) would, accordingly, overlap the impression *b* were it not for the spacings of the respective forming dies along the carrier bar 24.

The number of positions in which the dies may be mounted in spaced relation along the carrier bar is inherently limited by the length of the carrier bar. The number of available positions, however, is such it would be impossible, as a practical matter for a watchman to arrive at station *m*, in the illustrated example, before the tape had moved through the clock for a distance resulting in sufficient spacing of the impressions *a* and *m*, the dies for which are correspondingly mounted on the carrier bar 24.

It will be apparent that various modifications may be made in the above described embodiment of the invention and that accordingly the invention should be determined in scope by the following claims.

I claim:

1. A watchman's clock recorder key for forming indicia on record means within a watchman's clock, including an indicia-forming member and

a carrier therefor, a frame for said carrier including guide means providing for translation of the carrier and indicia-forming member in at least one plane between active and inactive positions, said frame having a first opening through which at least a portion of the carrier may move when the indicia-forming member is translated toward its active position, resilient means exclusively supporting said carrier in said plane of movement and urging the carrier toward its inactive position, and means forming a second opening in said frame affording access to said carrier at a point spaced from the first opening whereby the carrier may be displaced toward its active position.

2. A watchman's clock recorder key for forming indicia upon record sheet means within a watchman's clock, comprising male and female die members, a carrier for one of said die members, a frame for supporting said carrier including guide means providing for translation of said carrier and one die between active and inactive positions, resilient means biasing said carrier toward said inactive position, means supporting the other of said dies in operative relation with respect to said one die, means forming a first opening in said frame through which at least a portion of the carrier may move when the indicia-forming member is translated toward its active position, and means forming a second opening in the frame affording access to the carrier at a point spaced from the first opening whereby the carrier may be displaced toward its active position.

3. A watchman's clock recorder key for forming indicia upon record sheet means within a watchman's clock, comprising male and female die members, a carrier for one of said die members, a frame for supporting said carrier including guide means providing for translation of said carrier and one die between active and inactive positions, resilient means biasing said carrier toward said inactive position, means forming an opening in the frame affording access to the carrier whereby the carrier may be displaced by means external to said key toward its active position against the action of said resilient means, means supporting the other of said dies in operative relation with respect to said one die, said resilient means and said guide means being adapted to permit limited movement of said carrier in addition to and independently of said translational movement to facilitate cooperative action of said male and female die members.

4. In a watchman's clock recorder key for marking a record sheet within a watchman's clock, a frame, male and female die members, an elongated carrier for one of said die members mounted in said frame for translational movement along a substantially straight line normal to the longitudinal axis thereof, said carrier being adapted to support said one die member at any one of a plurality of positions along the length thereof, a second carrier member rigidly mounted with respect to said frame for supporting the other of said die members to be engaged by the movably mounted one die, said second carrier being adapted to support said other die member at any one of a plurality of positions corresponding to the position of said one die, and means forming an opening in the frame affording access to the carrier on the opposite side thereof from said one die member whereby the carrier may be displaced to bring the two die members into cooperative relationship.

5. In combination, a watchman's clock recorder key including indicia-forming means having active and inactive positions and releasable locking means for maintaining said indicia-forming means in its inactive position, a key-house for receiving said key and an unlocking member mounted in said key-house for coaction with said locking means when the key is inserted into said house to release said indicia-forming means.

6. In combination, a watchman's clock recorder key including indicia-forming means mounted for movement between active and inactive positions and releasable locking means for positively maintaining said indicia-forming means in its inactive position, a key-house for receiving said key, an unlocking member mounted in said key-house for coaction with said locking means for releasing said indicia-forming means when the key is inserted into said house, and actuating means in said key-house independent of said unlocking member for actuating said indicia-forming means.

7. In a watchman's clock recorder mechanism, 25 a recorder key having a shank portion and impression-rendering means supported therein for movement between inactive and active positions, a key-house assembly for receiving the shank of said key, means mounted in said key-house for actuating said impression-rendering means including a lever arm mounted for pivotal movement about a given axis, an actuating member mounted for pivotal movement about an axis perpendicular to the pivotal axis of said lever, and means carried by said actuating member for engaging said impression-rendering means in the key to displace the latter from its inactive to its active position.

8. In a watchman's clock recorder mechanism as set forth in claim 7, a click member mounted in said key-house assembly and interposed in the path of movement of said actuating member, said click member being adapted to produce an audible sound at such time as the actuating member has been displaced an amount necessary to move said impression-rendering means in the recorder key from its inactive to its active position.

9. In a watchman's clock recorder mechanism as set forth in claim 7 including a locking bar slidably mounted in said recorder key and normally interposed in the path of movement of said impression-rendering means to prevent movement thereof from its inactive to its active position, cam means for sliding said locking member out of locking position, and an unlocking member mounted in said key-house and adapted to displace said locking member through said cam means when the key is inserted in said key-house.

10. A watchman's clock recorder key including a shank portion, a carrier mounted in said shank portion for translational movement between operative and inoperative positions, a die member supported by said carrier, an arm member attached to said carrier and extending outwardly therefrom in alignment with the translational movement of the carrier, wall means formed in said shank portion for slidably receiving the arm and for constraining said carrier and arm for translational movement in a given plane between said operative and inoperative positions, spring means supporting said carrier and biasing the same toward its inoperative position, a locking bar movably mounted in said shank and

spring means biasing said bar toward a position at least partially interposed in the path of translational movement of said carrier, said wall means and locking bar cooperatively reacting against said arm and carrier respectively, to prevent translational movement of the carrier, and cam means for sliding said bar out of the path of movement of said carrier.

11. A watchman's clock recorder key including a shank portion, a carrier mounted in said shank portion for translational movement between operative and inoperative position, a die member supported by said carrier, an arm member attached to said carrier and extending outwardly therefrom in alignment with the translational movement of the carrier, wall means formed in said shank portion for slidably receiving the arm and for constraining said carrier and arm for translational movement in a given plane between said operative and inoperative positions, spring means supporting said carrier and biasing the same toward its inoperative position, a locking bar movably mounted in said shank and spring means biasing said bar toward a position at least partially interposed in the path of translational movement of said carrier, said wall means and locking bar cooperatively reacting against said arm and carrier respectively, to prevent translational movement of the carrier, a link pivotally mounted in said shank adjacent said locking bar and adapted to be swung into engagement with said bar to slide the latter out of the path of movement of said carrier.

12. A watchman's clock recorder key as set forth in claim 11, including, in combination, a key house having a channel for receiving said key and a member mounted in said key house and interposed in the key-receiving channel for swinging said pivotally mounted link when the key is fully received in said channel.

13. A watchman's clock recorder key comprising a frame having a chamber formed therein, an elongated carrier mounted in the chamber for translational movement between inoperative and operative positions and in directions normal to the longitudinal axis of the carrier, a perpendicularly extending arm member mounted on the carrier at any random position along the length thereof, said arm carrying indicia-forming means on its free end, the axis of the said arm being substantially aligned with the direction of carrier movement, means forming an opening in the frame affording access to the opposite side of the elongated carrier from the perpendicularly extending arm member whereby the carrier may be displaced by actuating means external to said key and guide bearing means formed in the frame for slidably receiving the arm to afford translational movement of the carrier and to constrain the carrier against excessive angular and longitudinal movement.

14. A watchman's clock recorder key as set forth in claim 13, said frame including a movable locking member mounted in the frame and adapted to be moved between a first position in which it is interposed between the inoperative and operative positions of the carrier and a second position free of the carrier, said guide bearing means of the frame and said movable member reacting cooperatively against said arm and one end of the carrier, respectively, to prevent movement of the carrier from its inoperative to its operative positions.

15. A watchman's clock recorder key, as set forth in claim 14, including a link member adapted to be actuated upon insertion of the key into a watchman's clock for moving said movable member to its second position.

16. In recording mechanism for watchmen's clocks, a recording key including a frame, an elongated carrier mounted in the frame for translational movement in a direction normal to the longitudinal axis thereof, and an indicia-forming member mounted at a random position along the longitudinal axis of the carrier, and actuating mechanism adapted to be carried by a watchman's clock for causing the indicia-forming member to engage record means within the clock, said actuating mechanism including an actuating member mounted for pivotal movement about an axis parallel to the longitudinal axis of the carrier in the recording key, the axis of pivotal movement being spaced laterally of the carrier when the key is inserted in the clock, said actuating member having a portion adapted to overlie the carrier, said overlying portion having bearing means for engaging the carrier at at least two spaced apart points along the longitudinal axis thereof, whereby pivotal movement of said actuating member causes said carrier to be displaced in translation to form indicia on the record means within the clock regardless of the position of the indicia-forming member along the longitudinal axis of the carrier.

17. Apparatus as set forth in claim 16 including a control lever arm member in the clock pivoted on an axis transverse with respect to that of the actuating member for pivoting the latter to displace the carrier in the key in translation.
